H. P. CLAUSEN,
TELEPHONE EXCHANGE SYSTEM,
APPLICATION FILED DEC. 13, 1916.

1,272,221.

Patented July 9, 1918.

UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,272,221.

Specification of Letters Patent.

Patented July 9, 1918.

Application filed December 13, 1916. Serial No. 136,625.

To all whom it may concern:

Be it known that I, HENRY P. CLAUSEN, a citizen of the United States, residing at Mount Vernon, in the county of Westches- 5 ter and State of New York, have invented certain new and useful Improvements in Telephone-Exchange Systems, of which the following is a full, clear, concise, and exact description.

10 This invention relates to telephone exchange systems, and more particularly to such systems in which trunk circuits are employed in completing connections between subscribers.

15 An object of this invention is provision of improved signaling means for such systems, whereby the work of the terminating operator is greatly simplified.

In accordance with a feature of this invention, apparatus is provided at the originating office by means of which the originating operator may determine which of two subscribers on a line to which the other end of a trunk circuit is connected, is signaled.

25 In accordance with another feature of this invention, the trunk circuit is provided with a signaling device associated with the incoming end thereof and operating when a link circuit is connected with the outgoing end thereof to furnish a signal and operating intermittently upon the subsequent disconnection of the link circuit from the outgoing end of the trunk, while the incoming end is connected with the telephone line, 30 the receiver of which is off the switchhook.

35 This invention is illustrated in the accompanying drawings, in which—

Figure 1 shows a trunk circuit, the outgoing end of which is equipped with duplicate jacks and a polarized relay for determining which of two parties on a line is to be signaled; and

40 Fig. 2 shows a cord circuit employed at the originating office and equipped with a reversing key for reversing the polarity of the battery connected with the outgoing end of the trunk circuit. When the reversing key is employed, the outgoing end of the trunk circuit may be equipped with only 45 one jack.

Throughout the various figures, the same reference characters will be used to designate the same pieces of apparatus.

50 In Fig. 1 there is shown a trunk circuit A extending between a first and a second

central office. A cord circuit B adapted for connection with the outgoing end of the trunk circuit A is located at the first central office. The outgoing end of the trunk is equipped with duplicate jacks 5 and 6, the 50 wiring of the tip and ring contacts thereof being reversed. Associated with the outgoing end of the trunk circuit is a polarized relay 7, poled so that it does not operate when the cord circuit B is associated with 55 the jack 5, but does operate when the plug of the cord circuit B is associated with the jack 6. A telephone line C terminates at the second central office. The line C is provided with two stations D and E, the call 70 bell at station D being connected between the ring side of line and ground and the call bell at station E being connected between the tip side of line and ground.

Referring to the operation of the system 75 shown in Fig. 1, the operator at the first central office having received an order for connection with station D on line C which terminates at the second central office, communicates with the operator thereat over 80 an order wire circuit (not shown) and receives a trunk assignment. Assuming that trunk circuit A has been assigned, the operator at the first central office inserts the plug of cord circuit B into jack 5, thereupon causing the operation of relay 8 to light lamp 9 over a circuit from battery, through the lamp, through the alternate contact of relay 8, lower normal contact of relay 10 and resistance 11 to ground. The operator 90

at the second central office, observing the lighted condition of lamp 9, inserts the plug of trunk circuit A into the jack of line C, whereupon relay 10 of the trunk circuit and cut-off relay 12 of line C operate. The operation of relay 10 causes the operation of relay 15 over a circuit from battery through the winding of relay 15, normal contacts of relay 16 and tripping relay 17, lower alternate contact of relay 10, alternate contact 100 of relay 8, winding of relay 10, sleeve contacts of the plug and jack and the winding of cut-off relay 12 to ground. The winding of relay 15 which is of low resistance is now connected in parallel with the lamp 9 which is thereby extinguished. The operation of relay 15 connects a source of alternating current 20 to the ring contact of the plug through the winding of tripping relay 17, left-hand normal contact of switching relay 110

21 and upper alternate contact of relay 15. The call bell at station D on line C, which is connected between the ring side of line and ground, is operated by current from source 5 20 over the path just traced. The subscriber at station D, responding, causes the operation of tripping relay 17, whereupon relay 16 operates, locks up and short-circuits relay 15, which releases to remove ringing current from the line. Relay 15, in releasing, 10 also completes the circuit for the supervisory relay 22, which thereupon operates over the line to include the right-hand winding of relay 8 in parallel with the left-hand winding thereof and the winding of the polarized relay 7, for the well-known purpose of causing the actuation of the supervisory relay in the cord circuit. At the conclusion of the conversation, the restoration of the receiver 15 to the switchhook by the subscriber D causes the release of supervisory relay 22, whereupon the supervisory relay in the cord circuit releases, lighting the supervisory lamp controlled thereby to furnish a disconnect 25 signal. The removal of the plug of the cord circuit B from the jack 5 by the operator at the first central office causes the release of relay 8, which, in releasing, permits lamp 9 to light to furnish a disconnect signal to the 30 operator at the second central office, who may thereupon remove the plug from the jack of line C, thereby restoring all apparatus to normal condition.

Should station E on line C have been desired, the operator at the first central office would have inserted the plug of the cord circuit B into the jack 6, whereupon relay 8 would operate as before described, and polarized relay 7 would operate to cause the 40 operation of switching relay 21 to switch the source of ringing current 20 from the ring to the tip side of the line. The connection may then be completed as before described.

45 If, while the receiver at either station D or E is off the switchhook and while the plug of the trunk circuit is connected with line C, the operator at the first central office by mistake removes the plug of the cord circuit B from the corresponding jack of the trunk circuit, lamp 9 will be lighted intermittently to furnish a signal to the second central office operator, indicating that fact. The intermittent operating circuit for the 55 lamp 9 may be traced from battery through the lamp, and a parallel path from battery through interrupter 25, contact 26 of relay 10, lower contact of supervisory relay 22, normal contact of relay 8, joining the path 60 through the lamp 9 at point 27, the circuit then being traced through the winding of relay 10, sleeve contacts of the plug and jack and the winding of cut-off relay 12 to ground. This intermittent operation of lamp 65 9 identifies the trunk circuit from which

the first central office operator has mistakenly disconnected the plug of the trunk circuit, so that the second central office operator may communicate with the first central office operator over an order wire circuit (not shown), requesting that the cord circuit be reconnected with the trunk circuit. 70

In Fig. 2 there is shown a cord circuit B for use at the first central office, this cord circuit being equipped with a reversing key 75 50, by means of which the polarity of the battery connected to the outgoing end of the trunk circuit may be reversed. When a cord circuit, equipped with a reversing key such as shown in Fig. 2, is used, the outgoing end 80 of the trunk circuit may be equipped with only one instead of two jacks, the operation of the polar relay 7 then being controlled by the position of the switching key. 85

What is claimed is:

1. A telephone exchange system comprising a trunk circuit extending from a first to a second central office, a telephone line terminating at the second central office and connected with the trunk circuit, a source of 90 signaling current at the second central office, switching means controlled by the operator at the first central office for determining the side of the line over which current from said source is to be projected, and 95 means for connecting the source of signaling current to the line.

2. A telephone exchange system comprising a trunk circuit extending from a first to a second central office, a telephone line terminating at the second central office and connected with the trunk circuit, a source of 100 signaling current at the second central office, a polarized relay controlled by the operator at the first central office for determining 105 the side of the line over which current from said source is to be projected, and means for connecting the source of signaling current to the line.

3. A telephone exchange system comprising a trunk circuit extending from a first to a second central office, a telephone line terminating at the second central office and connected with the trunk circuit, a source of 110 signaling current at the second central office, duplicate jacks at the first central office reversely connected to the talking strands of the trunk circuit, a polarized relay bridged across the talking strands of the 115 trunk circuit for determining the side of the line over which current from said source is to be projected, a link circuit at the first central office, said polarized relay operating or not operating depending upon the jack with which the link circuit is connected, and 120 means for connecting the source of signaling current to the line.

4. A telephone exchange system comprising a trunk circuit extending from a first to a second switchboard, a telephone line ter- 125 130

minating at the second switchboard, a relay in the trunk circuit energized upon the connection thereof with the telephone line, a source of ringing current, a ringing relay 5 responsive to the energization of the first relay to connect the source of current to the telephone line, a link circuit at the first switchboard, means controlled by the connection of the link circuit with the trunk 10 circuit for determining the side of the line over which ringing current is to be projected, a third relay in the trunk circuit controlled over the connected telephone line, a signaling device in the trunk circuit, interrup- 15 ter mechanism, and an operating circuit for the signaling device and the interrupter mechanism established upon the subsequent disconnection of the link circuit from the trunk circuit while the first and third relays 20 are energized.

5. A telephone exchange system comprising a trunk circuit extending from a first to a second switchboard, a telephone line terminating at the second switchboard, a relay in the trunk circuit energized upon the connection thereof with the telephone line, a source of ringing current, a ringing relay responsive to the energization of the first relay to connect the source of ringing current 25 with the telephone line, a link circuit at the first switchboard, a polarized relay in the trunk circuit controlled by the connection of the link circuit therewith for determining the side of the line over which ringing current is 30 to be projected, a third relay in the trunk circuit controlled over the connected telephone line, a signaling device in the trunk circuit, interrupter mechanism, and an operating circuit for the signaling device and 35 the interrupter mechanism established upon the subsequent disconnection of the link circuit from the trunk circuit and including contacts of the energized first and third relays.

45. 6. A telephone exchange system comprising a trunk circuit extending from a first to a second central office, a telephone line terminating at the second central office and connected with the trunk circuit, a signaling 50 device in the trunk circuit, a relay in the trunk circuit controlled over the telephone line, a relay controlled over the trunk circuit from the first central office, and means controlled by both relays for causing the in- 55 termittent operation of the signaling device.

7. A telephone exchange system comprising a trunk circuit extending from a first to a second central office, a telephone line terminating at the second central office and 60 connected with the trunk circuit, a signaling device in the trunk circuit, a relay in the trunk circuit controlled over the telephone line, a second relay in the trunk circuit controlled over the trunk circuit from the first 65 central office, and an interrupter brought

into circuit relation with the signaling device upon the deenergization of the second relay while the first relay is energized, thereby causing the intermittent operation of the signaling device. 70

8. A telephone exchange system comprising a trunk circuit extending from a first to a second switchboard, a link circuit at the first switchboard, a signaling device in the trunk circuit operated upon the connection of the link circuit therewith, a telephone line terminating at the second switchboard and connected with the trunk circuit, and means responsive to the disconnection of the link circuit from the trunk circuit to cause 75 the intermittent operation of the signaling device. 80

9. A telephone exchange system comprising a trunk circuit extending from a first to a second switchboard, a link circuit at 85 the first switchboard, a relay in the trunk circuit energized upon the connection of the link circuit therewith, a signaling device in the trunk circuit operated upon the energization of the relay, a telephone line terminating at the second switchboard, means in the trunk circuit responsive to the connection thereof with the telephone line to stop the operation of the signaling device, and means rendered effective upon the deenergization 90 of the relay when the link circuit is disconnected from the trunk circuit to cause the intermittent operation of the signaling device. 95

10. A telephone exchange system comprising a trunk circuit extending from a first to a second switchboard, a link circuit at the first switchboard, a signaling device in the trunk circuit operated upon the connection of the link circuit therewith, a telephone line terminating at the second switchboard, a relay in the trunk circuit responsive to the connection thereof with the telephone line for stopping the operation of the signaling device, and an intermittent operating circuit for the signaling device established upon the subsequent disconnection of the link circuit from the trunk circuit thereby causing the intermittent operation of the signaling device. 100

11. A telephone exchange system comprising a trunk circuit extending from a first to a second switchboard, a link circuit at the first switchboard, a relay in the trunk circuit energized upon connection of the link circuit therewith, a signaling device in the trunk circuit operated upon the energization of the relay, a telephone line terminating at the second switchboard, means in the trunk circuit responsive to the connection thereof with the telephone line for stopping the operation of the signaling device, a relay in the trunk circuit controlled over the telephone line, and an intermittent operating circuit for the signaling device 110

115

105

130

established upon the subsequent deenergization of the first relay while the second is energized.

12. A telephone exchange system comprising a trunk circuit extending from a first to a second switchboard, a link circuit at the first switchboard, a relay in the trunk circuit energized upon connection of the link circuit therewith, a signaling device in the 5 trunk circuit operated upon the energization of the relay, a telephone line terminating at the second switchboard, means in the link circuit responsive to the connection thereof with the telephone line for stopping 10 the operation of the signaling device, a relay in the trunk circuit controlled over the telephone line, interrupter mechanism, and a circuit including the interrupter mechanism and the signaling device established 15 through engaged contacts of the above two relays upon the deenergization of the first while the second is energized.

13. A telephone exchange system comprising a trunk circuit extending from a 20 first to a second switchboard, a link circuit at the first switchboard, a relay in the trunk circuit energized upon the connection of the link circuit therewith, a signaling device in the trunk circuit operated upon the energization of the relay, a telephone line terminating at the second switchboard, a relay in 25 the trunk circuit responsive to the connec-

tion thereof with the telephone line for stopping the operation of the signaling device, a third relay in the trunk circuit controlled over the telephone line, and an intermittent operating circuit for the signaling device established upon the subsequent deenergization of the first relay while the second and third are energized. 35

14. A telephone exchange system comprising a trunk circuit extending from a first to a second switchboard, a link circuit at the first switchboard, a relay in the trunk circuit energized upon the connection of the link circuit therewith, a signaling device in the trunk circuit operated upon the energization of the relay, a telephone line terminating at the second switchboard, a relay in the trunk circuit responsive to the connection thereof with the telephone line for stopping the operation of the signaling device, a third relay in the trunk circuit controlled over the telephone line, interrupter mechanism, and an operating circuit for the signaling device and the interrupter mechanism including engaged contacts of the three relays established upon the subsequent deenergization of the first relay while the second and third are energized. 45 50 55 60

In witness whereof, I hereunto subscribe my name this fourth day of December A. D., 1916.

HENRY P. CLAUSEN.
